UNITED STATES PATENT OFFICE.

ARTHUR W. NEWMAN, OF PHILADELPHIA, PENNSYLVANIA.

HOSIERY.

1,017,310.

Specification of Letters Patent. Patented Feb. 13, 1912.

Application filed March 15, 1910. Serial No. 549,461.

To all whom it may concern:

Be it known that I, ARTHUR W. NEWMAN, a citizen of the United States, residing in the city and county of Philadelphia, State 5 of Pennsylvania, have invented a new and useful Improvement in Hosiery, of which the following is a specification.

It is well known that stocking supporters often pull upward on the stocking and strain 10 the same so as to cause what is known as "drop stitches." These often extend a greater portion of the length of the stocking and are not only unsightly but soon render the stocking useless or necessitates mending 15 thereof.

My invention is designed to stop the progress of these drop stitches and it consists in providing the stocking with means forming a barrier to the further downward tearing 20 of the stocking, said means being composed of a line of stitches which unite the courses and wales of the knit fabric along said line.

In the drawings:—Figure 1 represents a side elevation of a portion of a stocking 25 embodying my invention. Fig. 2 represents a vertical section thereof showing the interior of the stocking. Fig. 3 represents a longitudinal section of another form of a stocking to which the invention is applied 30 cable.

Similar numerals of reference indicate corresponding parts in the figures.

Referring to the drawings:—1 represents a portion of a stocking which excepting the 35 feature of my invention applied thereto is of usual construction.

2 designates the barrier which is formed of a line of stitches extending circumferentially around the web portion of the leg of 40 the stocking a sufficient distance below the hem or welt fastening 3 and is independent of the same, a stocking supporter being shown as connected with the portion 1 in usual manner. The barrier is formed of a line of stitches 45 which unite the courses and wales of the knit fabric along said line wherefore should said supporter draw upwardly any of the

vertical wales with which it engages and thereby disintegrate or distort the fabric of the stocking at the sides of said wales as 50 shown at 4 in Fig. 1, such disintegration or distortion will be resisted by the line of stitches 2 which acts as a barrier to the further advance of the same, and so the main portion of the stocking especially below the 55 knee will remain intact and free of said objectionable feature.

In Fig. 3 the hem or welt is of a lengthened order in which case the supporter is attached to the stocking between the fastening 3 of said hem or welt and the top of the stocking, the line of stitches 2 serving as a barrier to the advance of any downward raveling or distortion of the stocking which may occur below the hem or welt fastening 65 3.

Having thus described my invention what I claim as new and desire to secure by Letters Patent, is:—

1. A stocking provided on its leg portion 70 with a barrier for the purpose described, the same being composed of a line of circumferentially-disposed stitches imposed on the knit fabric and adapted to unite the courses and wales of said fabric along said line. 75

2. A stocking provided on its leg portion with a barrier for limiting the downward progress of "drop stitches" due to upward strain exerted on the stocking, said barrier being composed of a circumferentially-disposed line of stitches uniting the courses and wales of the knit fabric along said line. 80

3. A stocking having, in the single web portion, one or more courses of sewing stitches extending around the web. 85

4. A stocking having, below the welt or hem, and within the single web of which the leg is composed, one or more courses of sewing stitches extending around the web.

ARTHUR W. NEWMAN.
